UNITED STATES PATENT OFFICE.

IRA FILSON, OF SPRINGFIELD, OHIO.

SAFETY DEVICE FOR HEATERS.

No. 867,355.

Specification of Letters Patent.

Patented Oct. 1, 1907.

Application filed May 28, 1906. Serial No. 319,129.

To all whom it may concern:

Be it known that I, IRA FILSON, a citizen of the United States, residing at Springfield, in the county of Clark and State of Ohio, have invented certain new and useful Improvements in Safety Devices for Heaters, of which the following is a specification, reference being had therein to the accompanying drawings.

This invention relates to safety devices for heaters, and is designed more particularly for use in connection with heaters using gas as a fuel. Natural gas is very largely used for this purpose, and is frequently subject to great variations in pressure, which sometimes extinguish the fires when the pressure falls, causing danger of asphyxiation and explosion when the pressure again rises, and which sometimes cause overheating, with its attendant dangers of fire, when the pressure rises too high.

It is the object of my present invention to provide a safety device for use in connection with a gas heater which will serve, in its most highly developed form, to not only give a warning signal, but also positively shut off the supply of gas, in case the temperature of the heater rises above or falls below certain predetermined but adjustable limits.

To these ends my invention consists in certain novel features which I will now proceed to describe, and will then particularly point out in the claims.

In the accompanying drawings, Figure 1 is a perspective view of an apparatus embodying my invention in one form; Fig. 2 is a detail front elevation of the shut-off mechanism; Fig. 3 is a side elevation of the same, partly in vertical section; Fig. 4 is a detail top plan view of the shifting lever which operates the shifting valve; Fig. 5 is a side elevation of the thermostat and its associated parts; Fig. 6 is a front elevation of the same; Fig. 7 is an enlarged detail sectional view, taken on the line *x x* of Fig. 6 and looking in the direction of the arrows; Fig. 8 is a plan section, taken on the line *y y* of Fig. 7 and looking in the direction of the arrows; Fig. 9 is a detail sectional view, taken on the line *z z* of Fig. 8 and looking in the direction of the arrows; Fig. 10 is a diagrammatic view illustrating the electric circuits of the apparatus; and Fig. 11 is a detail view of a modification.

In the said drawings, in which I have shown an apparatus embodying my invention in its preferred form, 1 indicates the main gas-supply pipe of a house, the same being provided with a shut-off valve or stop-cock 2, of any approved form, that shown being a well known form of plug valve comprising a casing 3, and a plug valve 4 rotatable therein to open or close the pipe 1 and thereby control the flow of gas through said pipe. In the present instance, the arrangement is such that the valve is open and the gas can flow through said pipe when the parts are in the position shown in full lines in Figs. 1, 2 and 3, while the valve is closed and

the flow is stopped or diminished when the parts are in one or the other of the two positions shown in dotted lines in Fig. 2 of the drawings. To effect the positive movement of this valve, the stem 5 thereof has secured to it by a screw bolt 6 a cross head 7, comprising a body 8, and parallel plates 9 arising above the body and connected by a pivot bolt 10. On this bolt is pivoted the lower end of a lever 11, the upper end of which consists of an enlarged head to give weight to the said upper end, the same consisting preferably of heavy metallic blocks or plates 12 and 13, secured to the upper end of the lever 11 and somewhat offset with respect to said lever and each other. These offsets provide recesses or spaces for springs 14 and 15, which serve not only as detents to hold the lever 11 normally in upright position, but also as impulse springs to give to said lever a primary impulse or start from its normal upright position either to the right or to the left, according to the requirements of the apparatus. The spring 14 is secured on the inner face of the plate 12 by means of a screw bolt 16, which secures the lower end of said spring to said plate. The upper end of the spring 14 is bent to form an inclined guard 17, which is adapted to engage the armature hereinafter referred to and permit the spring to pass the armature in one direction without injury of the parts. The spring 15 is similarly secured at its lower end to the inner face of the plate 13 by means of a screw bolt 18, and the upper end of said spring 15 is formed into an inclined guard 19 similar to the inclined guard 17 of the spring 14.

Coöperating with the springs 14 and 15 are two electromagnets 20 and 21. These magnets are supported on a shelf 22, which latter may be conveniently held in position by brackets 23, secured to the pipe 1 by clips 24. These electromagnets may be secured to the shelf 22 in any suitable manner, the construction which I have shown for this purpose comprising upwardly extending screw bolts 25, secured at their lower ends to the shelf 22, one pair of screw bolts for each magnet, the base 26 of which has the supporting pair of screw bolts passed upward through its ends, and nuts 27 being provided above and below said base to effect a vertical adjustment of the magnet. Said magnets extend down through the shelf 22 and have their poles projecting downward below the same, the pole 28 of the magnet 20 being immediately above the path of the spring 14, while the pole 29 of the magnet 21 lies above the path of the spring 15.

30 indicates an armature for the magnet 20, consisting 105 preferably of a spring of magnetic material, having one end secured to the under side of the shelf 22 by a screw 31, its other end lying below the pole 28 of the magnet 20 and terminating in a lip or flange 32, which is adapted to engage the upper end of the spring 14, as shown more 110 particularly in Fig. 2 of the drawings. 33 indicates a similar spring armature for the magnet 21, secured

to the shelf 22 at 34 and having its free end located below the pole 29 of the magnet 21 and provided with a lip or flange 35 to engage the upper end of the spring 15.

From an examination of Fig. 2 of the drawings, it will be seen that when the parts are in the position shown in full lines, the cross head 7 is horizontal, the shifting lever 11 vertical, and the parts are held in this position by the engagement of the springs 14 and 15 with the armatures 30 and 33, said armatures engaging said springs on opposite sides so as to prevent movement of the upper end of the lever 11 in either direction, the springs being, however, bent and under tension when thus engaged. Assuming that the magnet 20 is energized, the armature 30 will be drawn up into contact with the pole piece thereof, thereby disengaging said armature from the spring 17. This leaves the lever 11 free to fall towards the left of Fig. 2, it being prevented from falling toward the right by the engagement of the spring 15 with the armature 33, which engagement is still maintained. The lever 11 being vertical, some active force is required to start its fall, and, in the present instance, where the magnet 20 is assumed to be energized and armature 30 and spring 14 to be disengaged, it is the bent or tensioned spring 15 which is still in engagement with the armature 33 that gives the initial impulse to the lever 11 by moving its upper end over toward the left in Fig. 2 as soon as the spring 14 and armature 30 are disengaged and permit such movement. After the lever 11 has started to fall its velocity increases rapidly, of course, and said lever strikes an abutment 36 on the cross head 7 to the left of the pivot 37 of the shifting lever, its impact being rendered greater by reason of the weight of its upper end. The cross head 7, thus struck by the weight of the lever, turns with the same and thereby closes the shut-off valve 2. When the magnet 21 is energized and the armature 33 disengaged from the spring 15, the spring 14 gives the initial impulse to displace the lever 11, and said lever falls to the right of Fig. 2, striking against an abutment 38, which, when the parts are in normal position, lies somewhat lower than the abutment 36, thus permitting the lever 11 to move through a larger portion of its arc of movement before it strikes the abutment and begins to move the cross head along with it. The total movement of the lever 11 being the same, in the construction shown, whether it falls to the right or to the left, the range of movement of the cross head is less when the lever falls to the right, owing to the difference in position of the abutments 36 and 38. The construction is such that the fall of the lever to the right does not entirely close the stop-cock and cut off the flow, but acts to partially close said stop-cock and diminish the flow. The particular construction illustrated by which this result is obtained is designed for use with an ordinary stop-cock, having its ports symmetrically arranged, so that movement to an equal extent in either direction from the normal position will always produce the same result in diminishing or cutting off the flow. Of course, by the use of a specially designed valve or stop-cock, the particular means just described for varying the amount of movement of the cross head and valve according as the lever falls in one direction or the other may be dispensed with.

The electromagnets 20 and 21 are controlled by a thermostat shown in Fig. 1 and illustrated in detail

in Figs. 5 to 9 of the drawings, inclusive. 39 indicates a gas stove or other gas heater, having a stove pipe 40 for the escape of the products of combustion, a section of which is shown in Figs. 5, 6 and 7, the same being employed for the support of the thermostat just referred to. This thermostat comprises a lever 41, pivoted at 42 to the interior of the stove pipe section, and extending across said interior and out through a vertical slot 43 in the same. The movements of this lever are controlled by an expansion bar 44, pivoted at its upper end to the lever 41, as indicated at 45. The lower end of said expansion bar is provided with a nut 46, mounted on a threaded shaft 47 which is swiveled in the pipe 40 and provided with a thumb piece 48 by means of which said screw 48 shaft may be turned. The lengthening and shortening of the bar 44 by reason of changes of temperature in the pipe 40 cause an upward and downward movement of the free projecting end of the lever 41, and the range of this movement is controlled by the screw 48 shaft 47, rotation of which gives to the projecting end of the lever 41 an initial position which is either higher or lower with respect to the contact pieces hereinafter referred to, according to the direction in which the shaft 47 is turned.

Provision is made for indicating visually the position to which the lever 41 is set by the mechanism just described. To protect the mechanism employed for this purpose and also the contacts which co-operate with the lever 41, there is secured to the pipe 40 a box or housing 49, having on its front face, as shown in Fig. 6, a dial 50, with suitable indicating figures thereon, the box having a hinged top or cover 51, secured by a catch 52, said hinged cover giving access to the interior of the box. The dial 50 has co-operating with it an index or pointer 53, secured to the front end of a shaft 54, said end projecting outward beyond the front of the box to receive said index or pointer outside of the same. The shaft 54 is supported in a bracket 55 within the box, and has mounted on it a pinion 56, with which meshes a gear segment 57, pivoted at 58 in the bracket 55. To this gear segment there is pivoted at 59 the lower end of a link 60, the upper end of which is pivoted at 61 to the free end of a lever 62, pivoted at its other end, as indicated at 63, to a bracket 64. The lever 62 is engaged by the forward end of the lever 41, the connection being preferably that shown, in which the lever 62 is provided with a slot 65, through which the lever 41 passes and slides, the lever 62 having a pin 66 which extends across the slot 65 and passes through a slot 67 formed longitudinally in the lever 41. By reason of the connection just described, turning the thumb piece 48 to shift the position of the lever 41 will correspondingly turn the index or pointer 53 and thereby move said pointer to conform to the initial position of the lever 41. The contacts hereinbefore referred to, indicated respectively by the reference numerals 68 and 69, are arranged respectively above and below the lever 41 in the path thereof, and it will be seen that if the lever be set to any given position, the precise increment of heat which will cause it to rise sufficiently to touch the upper contact 68 may be readily determined, and the scale of figures on the dial may be so arranged that for any given

position of the index 53, the figure to which said index points will indicate the temperature at which the lever 41 will be raised to a position such as to strike the contact 68. It will be understood that, when the device is in actual operation, the lever 41 will always be so adjusted that upon a decrease in temperature in the pipe 40 such as follows the extinction of the flame of burning gas in the stove or heater, the contraction of the bar 44 will draw the lever 41 down so as to cause it to bear upon the contact 69. When the device is not in use, the lever may be readily adjusted by means of the screw shaft 47 so as to remain fixed in a position between the two contacts and out of contact with both of them.

In Fig. 11 I have shown a modification of the connection between the expansion bar and contact lever, the former being indicated in this instance by the reference numeral 70, and the latter by the reference numeral 71. In this construction, an intermediate lever 72 is employed, pivoted at 73 to the pipe 40 and having the upper end of the expansion bar 70 pivoted to it at a point 74 near its own pivotal point 73. The lever 72 is pivotally and slidingly connected to the contact lever 71 at its free end, as indicated at 75, and the distance between the pivots 74 and 75 is greater than the distance between the pivots 73 and 74, so that the expansion of the bar 70 results in a correspondingly increased range of movement of the contact lever 71, thereby rendering the latter more sensitive to the variations of the length of the expansion bar than in the case of the direct connection such as is illustrated in Fig. 7.

The contacts 68 and 69 are mounted on an insulating block 76, each contact having a base portion 77 at right angles to its body portion, through which base portion passes an adjusting and clamping screw 78 and out through the wall of the box 49, its outer end receiving a thumb nut 79, which bears against the outer wall of the box. Each contact has an angularly arranged extension 80 of its base, which forms a convenient means for swinging the contact around the screw 78 as a pivot when the nut 79 is loosened. By this means the contacts 68 and 69 may be independently adjusted up and down relatively to the contact lever 41, thus forming an alternative means of adjustment of the contacts to the desired temperature, and one which may be employed to bring the actual contact into conformity with the indications of the pointer and dial in case of disarrangement of the device.

The lever 41 is connected to one terminal of a battery or other suitable source of electrical energy 81, the connection being shown as effected by means of a wire 82. The contact 68 is connected with the coil of the electromagnet 20 by a wire 83, while the contact 69 is connected with the coil of the electromagnet 21 by a wire 84. The other ends of the magnet coils are connected by branch wires 85 to a wire 86 which leads to the other terminal of the battery 81, and a switch 87 is located in this portion of the circuit, so as to make or break the same by hand. These circuits are shown diagrammatically in Fig. 10 of the drawings. It will be seen that when the temperature within the heater 39 and pipe 40 falls a sufficient extent by reason of the extinguishing of the fire through the cessation in the flow of gas, the arm 44 will cool

and contract, moving the lever 41 downward into contact with the contact 69. This closes the circuit which, starting from the battery, proceeds through the wire 82, lever 41, contact 69, wire 84, magnet 21, branch wire 85 and return wire 86 to the battery. The magnet 21 thereby becomes energized, the armature 33 is attracted and releases the lever 11, and the latter, being given its initial impulse by the spring 14, falls to the left in Fig. 2 of the drawings, and closes the stop-cock 2, thereby cutting off the flow of gas. On the other hand, if by reason of an excessive flow of gas or some other cause the temperature rises too high in the heater 39 and its pipe 40, the bar 44 will expand and move the lever 41 upward until it strikes the contact 68, whereupon the circuit will be closed from battery 81 through wire 82, lever 41, contact 68, wire 83, magnet 20, branch wire 85 and return wire 86 to the battery. This closed circuit energizes the magnet 20, attracts the armature 30, releases the lever 11 on the opposite side, and permits the spring 15 to give it an initial impulse which causes it to fall to the right in Fig. 2 of the drawings, partly closing the stop-cock 2 and diminishing the flow of gas. The position of the fallen lever will indicate whether the gas supply was affected because of failure of the gas supply or because of an excessive temperature, so that steps may be taken to remedy the matter. Of course, by bringing the lever 11 upright and again engaging it with the armatures 30 and 33, the stop-cock 2 may be again opened to permit the flow of gas to the heater.

It is deemed advisable to provide a signal or alarm which will be operated whenever the temperature passes the limits prescribed for it, and for this purpose I prefer to employ a bell 88, connected with the battery 81 through the medium of a wire 89, joined to the wire 82. The lever 11 is in electrical connection with the other terminal of the battery through a wire 90, joined to the wire 86. Wires 91 and 92 lead from the bell to contacts 93 and 94 respectively, said contacts being arranged on opposite sides of the pivotal axis of the lever, in a position such that when the lever falls to the right of Fig. 2 it will come into contact with the contact piece 93, and when the lever falls to the left in said figure it will come into contact with the contact piece 94. In the former case a circuit is established from battery 81, through wire 82, wire 89, bell 88, wire 91, contact 93, lever 11 and wires 90 and 86 back to the other terminal of the battery, the circuit thus closed operating the bell or alarm 88. In the latter case, when the lever falls to the left, the circuit is established from the battery through wire 82, wire 89, bell 88, wire 92, contact 94, lever 11, and wires 90 and 86 back to the other terminal of the battery, in which case the bell or signal 88 is also actuated. The switch 87 may be used to stop the sounding of the signal bell after it has attracted attention, and for this purpose the bell and switch may be conveniently arranged in one part of the house, say, for instance, a bedroom in an upper story, while the heater may be located in the same room or another room, or in the basement, and the balanced lever 11 and its controlling magnets may be located in still another portion of the structure, these latter being usually located in the basement or cellar, so that the stop-cock 2 may be placed in the supply

- pipe at a point between the source of supply of gas and the first branch pipes within the house. Thus, the location of the switch 87 in a convenient portion of the house avoids the necessity of descending to the cellar 5 to lift the lever 11 for the purpose of breaking the circuit at the contacts 93 and 94. It will be understood that some of the features of the construction just described are available in a structure where the lever 11 is not employed for the purpose of automatically closing 10 the stop-cock, since it may be seen, that the closing of the signal circuits on an undue rise or fall in temperature, will notify the occupants of the house and enable them to shut-off and regulate the gas by hand, if necessary.
- 15 I have described an apparatus embodying my invention in its most highly developed form, comprising both an automatic shut-off and alarm signal, operative upon either an excessive rise or fall in temperature, and so constructed as to indicate after its operation 20 whether the same was due to a rise or to a fall in temperature. But the invention, in its simpler forms, does not require the embodiment of all of these features, some of which may be omitted. For instance, one of the two contacts 68, 69, may be omitted, and the mechanism so organized as to respond only to an excessive rise or to an excessive fall in temperature. It is also apparent that while it is desirable that the lever, by falling in different directions when actuated by different conditions, should indicate the cause of the trouble, nevertheless, the apparatus may be simplified by causing the lever to fall always in the same direction, whether actuated by a rise or fall in temperature, since the gas will be shut off and the signal actuated in this case also, although the lever would not indicate the 35 actuating conditions.
- I wish it to be understood that I do not desire to be limited to the exact details of construction shown and described, for obvious modifications will occur to a person skilled in the art.
- 40 Having thus fully described my invention, what I claim is: new and desire to secure by Letters Patent, i.e.:
1. A safety device for heaters, comprising a gas supply pipe, a stop-cock controlling said pipe and having a laterally extended arm, a weighted lever pivoted near said stop-cock and arranged to strike said arm when released to operate said stop-cock, an electro-magnet having an armature which acts when free to prevent the fall of said lever, an electric circuit including said electromagnet and a source of electricity, and a circuit-closing device controlling the circuit and actuated by the temperature of the heater, substantially as described.
  2. A safety device for heaters, comprising a gas supply pipe, a stop-cock controlling the same, a normally upright lever acting to operate said stop-cock by its fall in either direction when released, two electromagnets, the armatures whereof support said lever on opposite sides, an electric circuit including said electromagnets, and a circuit-closing arm, contacts located on opposite sides of said arm and electrically connected with the respective magnets, and a thermostat controlled by the temperature of the heater and acting to move said circuit-closing arm against one or the other of said contacts as the temperature either rises or falls excessively, substantially as described.
  3. In a safety device for heaters, a stop-cock controlling the gas supply, and a normally upright lever acting to operate said stop-cock by its fall in either direction when released, in combination with two electromagnets, the armatures whereof engage and support said lever on oppo-
- site sides, means for energizing said electromagnets upon an undue rise or fall of temperature, respectively, and springs interposed between said magnets and armatures, whereby when one armature releases the lever the spring which engages the other armature gives the lever an initial impulse, substantially as described.
4. In a safety device for heaters, a gas supply pipe, a stop-cock controlling the same and provided with a cross head, a weighted lever pivotally mounted on the cross head and adapted to strike the same when it falls in either direction, means for holding said lever normally in upright position, and means for releasing said lever to cause it to fall in one direction or the other upon an undue increase or decrease in the temperature, substantially as described.
5. In a safety device for heaters, a stop-cock, a normally upright lever controlling the same and acting to operate said stop-cock by its fall in either direction, two electromagnets, the armatures whereof support said lever on opposite sides, an electric circuit including a source of electricity, a circuit-closing arm, and branch circuits including said electromagnets and contacts on opposite sides of said arm, and a shunt circuit including the lever, an alarm, and contacts arranged on opposite sides of said lever and electrically connected with said alarm, substantially as described.
6. In a safety device for heaters, the combination, with the outlet pipe of the heater, of a contact lever having one end extending into said pipe, a contact in the path of the outer end thereof, and an expansion bar located in said pipe and connected with the inner end of said contact lever, substantially as described.
7. In a safety device for heaters, the combination, with the outlet pipe of the heater, of a contact lever having one end extended into said pipe, contacts located on opposite sides of said contact lever, and an expansion bar located in said pipe and connected with the inner end of said contact lever, substantially as described.
8. In a safety device for heaters, the combination, with the outlet pipe of the heater, of a contact lever, a contact located in the path thereof, an expansion bar located in the pipe and connected at one end with the contact lever, and means for shifting the other end of said expansion bar to vary the distance between the contact lever and contact, substantially as described.
9. In a safety device for heaters, the combination, with the outlet pipe of the heater, of a contact lever, a contact located in the path thereof, an expansion bar located in the pipe and connected at one end with the contact lever, means for shifting the other end of said expansion bar to vary the distance between the contact lever and contact, and an indicating mechanism operating in unison with said lever, substantially as described.
10. In a safety device for heaters, the combination, with the outlet pipe of the heater, of a contact lever, contacts located on opposite sides thereof, an expansion bar located within the flue and connected at one end with the contact lever, and means for shifting the other end of said expansion bar to vary the position of said lever relatively to the contacts, substantially as described.
11. In a safety device for heaters, the combination, with the outlet pipe of the heater, of a contact lever pivotally mounted on said pipe and extending across the same, a contact in the path of said lever, a screw shaft mounted to rotate in said pipe, and an expansion bar having a threaded engagement with the screw shaft at one end, its other end being connected with the contact lever, substantially as described.
12. A safety device for heaters, comprising a gas supply pipe, a stop-cock controlling the same, a normally upright lever acting to close said stop-cock by its fall in one direction and to partly close said stop-cock by its fall in the opposite direction, two electromagnets, the armatures whereof support said lever on opposite sides, an electric circuit including said electromagnets, and a circuit-closing arm, contacts located on opposite sides of said arm, and electrically connected with the respective magnets, and a thermostat controlled by the temperature of the heater and acting to move said circuit-closing arm against one or the other of said contacts as the temperature either rises or falls excessively, substantially as described.

13. In a safety device for heaters, a gas supply pipe, a stop-cock controlling the same and provided with a cross head, a weighted lever pivotally mounted on the cross head, abutments differentially located on opposite sides of said cross head, whereby the cross head is moved to different extents according as the lever falls in one direction or the other and strikes one or the other of said abutments, means for holding said lever normally in upright position, and means for releasing said lever to cause it to fall in

one direction or the other upon an undue increase or decrease in the temperature, substantially as described. 10

In testimony whereof, I affix my signature in presence of two witnesses.

IRA FILSON.
